UNITED STATES PATENT OFFICE.

FRANK McLESKY AND WILLIAM P. W. JOHNSON, OF CHICAGO, ILLINOIS.

CURTAIN GUIDE.

Application filed October 31, 1921. Serial No. 511,552.

To all whom it may concern:

Be it known that we, FRANK McLESKY and WILLIAM P. W. JOHNSON, citizens of the United States, and residents of the city 5 of Chicago, county of Cook and State of Illinois, have invented certain new and useful Improvements in Curtain Guides, of which the following is a specification.

Our invention relates to new and useful 10 improvements in curtain guides and has for its object to provide means for guiding the curtain or shade to prevent the same from over-running the end of the roller during rolling and unrolling thereof.

15 Other objects will appear hereinafter.

The invention consists in the combinations and arrangements of parts hereinafter described and claimed.

20 The invention will be best understood by reference to the accompanying drawings forming a part of this specification, and in which,

Fig. 1 shows the guide means mounted in position on the curtain or shade,

25 Fig. 2 is a view of the actuating end of the roller and the attached guide means, as seen from the left-hand side in Fig. 1.

Fig. 3 is an end view of the roller and guide means, as seen from the right-hand 30 side in Fig. 1, and

Fig. 4 is a fragmentary view of the roller, showing the two guide members in section mounted in position on the two ends of the roller.

35 In the drawing our improved guide means is shown mounted on the ends of an ordinary roller 7 of a curtain or shade 8. Said guide means consist of two substantially cup-shaped members 10 and 11, provided with outwardly or radially extending integral flanges 12 and 13 which engage the edges of the shade or curtain, as shown in Fig. 1, and guide the same into proper position during rolling and unrolling thereof, thereby

40 also avoiding fraying of the curtain. The member 10 has its outwardly extending flange 12 positioned on the inner part and is provided on the outer part with an inwardly extending circular flange 14 engaging the end of the roller and forming an opening 15, through which the flat support-

ing and operating pin 16 of the roller 7 extends. The members 10 and 11 may be composed of wood or metal, or any suitable material. In mounting member 10 the customary metal cap located on this end of the roller is removed therefrom and the member 10 is driven on said end in place of said metal cap, being preferably glued thereon, or rigidly fastened thereon in some other 60 suitable manner. The member 11 has its flange 13 situated on the outer side, and in mounting said member a short cylindrical portion is cut from the end of the roller, leaving a reduced portion 17 upon which 65 the cup or cylindrical portion 18 of member 11 is firmly fastened, as by gluing it thereon, or it may be fastened in any other suitable manner. The usual round pin 19 situated at this end of the roller is removed before mounting member 11, and is driven through said member 11 and back into the 70 end of the roller, aiding the glue or fastening means to hold member 11 fast upon reduced portion 17 of the roller, usually made 75 of wood.

With our improved guide means the shade is prevented from over-running either end of the roller, which prevents the usual unsightly appearance and whereby the edges 80 of the shade or curtain are usually frayed. The guide means also adds to the appearance of the curtain or shade, and is inexpensive in manufacture and easy to apply.

While we have illustrated and described 85 the preferred form of construction for carrying our invention into effect, this is capable of variation and modification without departing from the spirit of the invention. We therefore, do not wish to be limited to the 90 precise details of construction set forth, but desire to avail ourselves of such variations and modifications as come within the scope of the appended claim.

Having described our invention, what we 95 claim as new and desire to secure by Letters Patent is:—

In combination with a shade having a roller provided with a circumferentially reduced portion at one end and the usual flat 100 pin and pawls at the other end, a cup-shaped member glued over said reduced portion, a

pin driven through said cup-shaped member and into said reduced end portion, and a cup-shaped member fastened over the opposite end of said roller and having an enlarged opening to receive said pin and pawls, said members being provided with radially extending flanges for guiding said shade.

In testimony whereof we have signed our

names to the foregoing specification in presence of two subscribing witnesses.

FRANK McLESKY.
WILLIAM P. W. JOHNSON.
